HOUSE NUMBER PLATE

Morris Sutton, 1653 Ocean Parkway, Brooklyn, N.Y.

Filed May 6, 1963, Ser. No. 74,757

Term of patent 3½ years

(Cl. D1—12)

FIG. 1.

FIG. 2.

FIG. 3.

FIG. 2 is a rear elevation view thereof, and

FIG. 3 is a sectional view taken on line 3—3 of FIG. 2.

The dominant features of my design reside in the portions shown in full lines.

I claim:

The ornamental design for a house number plate, substantially as shown and described.
